UNITED STATES PATENT OFFICE.

LOUIS MAXWELL POTTS, OF BALTIMORE, MARYLAND, ASSIGNOR TO AUSTIN McLANAHAN, OF BALTIMORE, MARYLAND.

TELEGRAPHIC RECEIVER.

1,229,202.

Specification of Letters Patent.

Patented June 5, 1917.

Application filed January 8, 1914. Serial No. 811,035.

To all whom it may concern:

Be it known that I, LOUIS MAXWELL POTTS, a citizen of the United States, residing at Baltimore city, State of Maryland, have invented certain new and useful Improvements in Telegraphic Receivers, of which the following is a specification.

The primary object of this invention is the production of a page printing telegraph receiver which shall be of as low cost to manufacture as is commensurate with operating efficiency; which shall be free from liability to get out of order and require as little adjustment from time to time as possible, and which shall be readily adaptable to use on present day commercial telegraph circuits.

Low cost of manufacture is attained in the present machine by a great reduction in parts, and by devising and designing these parts with a manufacturing end in view.

Certainty of operation and the reduction of adjustments are obtained primarily by eliminating the electrical factor as far as possible. In the present machine a single magnet constitutes the entire electrical equipment.

Adaptability to present day commercial circuits is attained by placing all the operations of the machine under the control of a single magnet so that the machine may be readily substituted for the usual sounder in a Morse circuit without requiring any other change in the receiving apparatus, or any change in the current or line equipment; by providing a machine which shall operate on a code at least as short as the Morse, and by providing a machine which is adapted for use without change on a line operated according to the Morse American closed circuit method as well as on a line operated according to the open circuit method.

In order to more fully describe my invention, reference will be had to the accompanying drawings wherein:

Figure 1, is a front elevation of a page printing telegraph receiver embodying one specific form of my invention;

Fig. 2, an end elevation thereof, with the selector removed.

Fig. 3, a diagram illustrating the principle of the combination disks, and also showing the combinations employed for the various signals;

Fig. 4, a vertical central sectional elevation of said machine;

Fig. 5, a detail vertical sectional elevation of the clutch on the main power shaft;

Fig. 6, a front elevation of one of the parts of said clutch;

Fig. 7, a fragmentary sectional elevation of the timing mechanism and controlling magnet;

Fig. 37, a developed view showing in side elevation the outline and setting of the various control cams and disks on the control shaft;

35 Fig. 38, a detail fragmentary sectional elevation of parts of the paper feed mechanism;

Figs. 39, 40 and 41, are detail views of the 40 correcting wheel ratchet, and a member of the clutch shown in Fig. 38;

Fig. 42, a detail sectional elevation of parts of the paper feed control mechanism;

Figs. 43 and 44, fragmentary detail sectional views to illustrate the operation of 45 the control roller clutch and associated parts, Fig. 43, showing said parts in their normal position and Fig. 44 showing them in the operated position;

Fig. 45, a fragmentary sectional top plan 50 of the control mechanism located within the casing at the right hand end of the machine, said view showing said casing removed;

Fig. 46, an end elevation of the machine, 55 looking at the right hand end thereof, with the casing which incloses the control mechanism removed;

Fig. 47, a detail fragmentary perspective view to illustrate the construction and operation of the printing, spacing, carriage return and paper feed mechanisms;

Fig. 48, a detail fragmentary top plan 60 of the type wheel and print hammer return control slide;

65 Fig. 49, a developed view showing the

outline and relative positions of the various control slides and pawls shown in Fig. 47;

Figs. 50 to 53, inclusive, are detail views of certain parts employed in the operation of spacing and returning the type wheel 70 and print hammer to the commencement of a line;

Fig. 54, a developed view showing the outline and relative setting of the selector canis and other parts mounted on the timing 75 shaft of the selector;

Fig. 55, a fragmentary detail sectional elevation, showing the parts illustrated in Fig. 4 mounted upon the selector timing shaft, and also showing the selector timing 80 shaft friction clutch;

Fig. 56, details of the positive coupling between the selector timing shaft and its clutch;

Fig. 57, a front elevation of the control 85 disk operated by the selector timing shaft which also forms a part of the coupling illustrated in Fig. 56;

Fig. 58, a fragmentary detail perspective view to illustrate the construction and operation of the type wheel shift mechanism;

Figs. 59 and 60, perspective views of two 90 of the control slides employed in said shift mechanism;

Fig. 61, a fragmentary detail perspective 95 view of parts of the mechanism shown in Fig. 58;

Fig. 62, a detail fragmentary elevation 100 showing parts of the type wheel shifting mechanism;

Fig. 63, a current diagram illustrating a system of signals which may be used with this machine;

Fig. 64, a diagram to illustrate the application of this machine to the usual American closed circuit method of operating Morse;

Fig. 65, a diagram showing the application 105 of this machine to the English method;

Fig. 66, is a diagram illustrating one way 110 of operating the transmitters of Figs. 64 and 65 so as to send signals such as illustrated in Fig. 63.

The operations of printing, spacing, lining, returning to the commencement of a new 115 line, and shifting the type wheel from one set of characters to another are, in this machine, all under the primary control of a selecting mechanism located at one end of the machine, and which is separately detachable as a whole from the body of the 120 machine without disturbing any of the parts.

This selecting mechanism as here shown comprises, among other parts, (see Figs. 7 to 25) a magnet 1 mounted for vertical adjustment by a milled screw 2, upon bracket 3, made fast to a fiber block 4 which forms one end of the selector casing. The sides of this casing consist of two metal plates 5 and 6 between which the block 4 and a 130

similar block 7, the latter forming the other end of the casing, are rigidly held.

The magnet 1 is provided with an armature 8, which is pivotally supported between brackets 9 and 10, fast upon block 4, and which is at all times under the tension of a spring 11 tending to pull it away from the magnet. This spring is adjustable by means of a milled screw 12.

16 The armature 8 extends through an opening 13 in block 4, and into the selector casing, where it acts to control the operation of a series of selector elements and the starting of a timing device.

15 This timing device comprises, among other parts, a balance 14 fast upon a shaft 15 journaled for rotation in plates 5 and 6. This balance, when released, oscillates under the control of a helical spring 16, having one end rigidly fastened to the balance at 17, and the other end clamped, as at 18, to a circular plate 19 rigidly secured by screws 19' to the side 6 of the selector casing. The screws 19' pass through slots 19" in plate 6, for permitting adjustment of plate 19 and spring 16. (See Figs. 15 and 18). The number of turns in this spring is a whole number lacking approximately 90°, according to the well known practice in 25 chronometer structure. The size of the wire of said spring, and the weight of the balance 14 are so chosen that one-half of a complete (forward and back) oscillation of the balance occupies the time necessary for 35 one unit impulse of the signal. This period of oscillation is chosen merely as being the most convenient, and is not necessarily essential. A unit impulse could correspond to a quarter or other period of the oscillation 40 of the balance. It is, however, important that the unit impulse correspond to some multiple of the period of the balance. The character of these signal impulses will be hereinafter more fully described.

45 The balance has on its circumference two mean time screws 20, which are used to bring the balance to the desired standard, and this is done by choosing screws of the proper weight. If the balance is too fast, a larger screw is inserted; if too slow, a smaller screw is used.

Also inserted in the rim of the balance are two rating screws 21, located about 90° from the screws 20. Screws 21 are used for the 55 purpose of changing the rate of the machine in words per minute to adapt it to different lengths of line, and different operating conditions. The balance is so constructed that it has a rate equal to the maximum rate desired, and this rate is brought down to that required, in any particular case, by the employment of the screws 21 of a size corresponding to the particular rate required.

The power which actually oscillates the 65 balance is transmitted to it through an es-

capement mechanism comprising an escape wheel 22 fast on a square shaft 23 herein-after to be referred to as the timing shaft; an anchor 24 fast on rock shaft 25; safety roller 26, fast on shaft 15; an impulse pin 27 fast on the said roller and adapted to engage a notch 28 in the lower end of the anchor, and a safety pin 29 adapted to engage passing hollow 29' in the safety roller. This escapement mechanism is substantially the same as that commonly known as the "lever escapement" used in the clock and watch-making art, so need not here be more fully described.

Escape wheel 22 has six teeth, so that three 80 complete oscillations of the balance will allow the timing shaft 23 to rotate one-half a revolution, which is the length of time required for the reception of a complete signal.

The starting and stopping of the balance 85 is controlled directly by a slide 30 mounted for vertical movement in slotted stationary guides 31 and 32 supported by plates 5 and 6, and is backed up at its lower end by a stop 33. This slide is at all times under pressure downward of a spring 34, and is provided with a nose which at times is adapted to extend into the path of and be engaged by a stop arm 35 made fast to the periphery of the balance. The nose of this slide is split as 90 at 36 to render the same slightly yieldable when struck by the stop arm 35. In the normal position of the parts, the balance 14 is at rest with stop 35 against the nose of slide 30, as shown in Fig. 7, at which time 100 spring 16 is under torsional stress.

Slide 30 is provided near its upper end with an arm 37 having a nose at all times in engagement under tension of spring 34, with the periphery of a cam 38 fast on timing 105 shaft 23. In the normal or position of rest of the parts, the nose of arm 37 engages one or the other of two diametrically opposite depressions or notches 38", in the periphery of cam 38.

Slide 30 carries a depending arm 39 pivoted thereto as at 40, and the lower end of this arm is movable in a guide 41 made fast to slide 30. (See Figs. 7, 8 and 9).

The arm 39 is at all times held between the 115 arms of a yoke 42 formed on the end of an arm of a bell crank lever 43.

Another arm 44 of this bell crank lever is provided with a nose which rests upon the periphery of a cam 38' which is a duplicate 120 of cam 38 and therefore provided with two diametrically opposite peripheral notches 38" similar to those of cam 38. The nose of arm 44 is held against cam 38' under tension of a spring 45. Cam 38' is fast on shaft 23 and 125 is alongside and adjacent cam 38.

The noses of arms 37 and 44 which engage with cams 38 and 38' respectively are relatively staggered so that when said cams rotate together, cam 38 will act to raise the 130

nose of arm 37 slightly before cam 38' acts in a similar way upon arm 44. The reason for this will appear later.

In the normal position of the parts, as shown in Fig. 7, the lower end of arm 39 lies just above the upper edge of armature 8. The function of the arm 39 and its operation in connection with its armature 8 will be hereinafter fully described.

10 The movement of armature 8 is limited by a slotted block 46 secured to guide 32 (see Figs. 10, 11 and 13).

15 In addition to starting the timing mechanism, the armature of magnet 1 selectively controls the operation of a series of selecting levers 46^a, 46^b, 46^c, 46^d and 46^e mounted in guides 31 and 32 respectively.

20 On the lower end of each of these levers is formed an offset or foot 47 adapted, as hereinafter described, to coöperate with armature 8, and movable each in an individual open end slot 48 in guide 32. In the normal position of levers 46^a-46^e, as shown in Fig. 13, the lower edges of feet 47 are slightly higher than the free end of armature 8 when the latter is in its normal or down position, and the feet 47 are of such length as to permit the end of the armature to pass up in front of them to the position 25 shown in Fig. 14. Armature 8 is broad enough to span the feet of all the selecting levers as well as arm 39, as shown in Fig. 10.

30 Each of the levers 46^a-46^e is provided near its upper end with two lugs 49 and 50 between which is formed a space into which extends an edge of the guide 31. Each lug 49 works in an individual open end slot 51 in the upper face of guide 31, and in addition to serving as a guide or support for its 35 lever, coöperates with a locking pawl 52, as hereinafter more fully described. There is one of these pawls 52 individual to each selecting lever, and they are mounted in slots 51 with their respective levers, and all pivoted upon a common fulcrum pin 53 carried by guide 31. Each pawl 52 is under pressure of an individual coil spring 54 which are within holes drilled in the guide 31.

35 Levers 46^a-46^e can move outward or to the left (Fig. 13) in the guides 31 and 32 at either the top or the bottom, but are normally held back by springs 55, one for each lever.

40 On the inner edge of each lever 46^a-46^e is formed a cam lug 56, the function of which is to coöperate with a series of five cams 57^a, 57^b, 57^c, 57^d and 57^e fast on the timing shaft 23, and lying in the same vertical planes respectively with levers 46^a-46^e. 45 These cams 57^a-57^e are all of the same shape, but are so mounted on shaft 23 that succeeding ones are angularly displaced 30° behind the preceding one about the axis of said shaft, and are held against lateral 50 movement by collars 58. The staggering of

these cams on shaft 23, as well as their fixed angular positions relative to escape wheel 23 and cams 38-38' is clearly shown in Fig. 54.

55 As shaft 23 rotates, cams 57^a-57^e successively engage cam lugs 56 on the selecting levers, and if armature 8 were in its down position, shown in Fig. 13, the foot of each of said levers would be kicked to the left by said cams. But, if at the time when cams 57^a-57^e engage levers 46^a-46^e, magnet 1 75 happens to be energized, armature 8 will then be in alinement with feet 47, as shown in Fig. 14, and instead of the levers 46^a-46^e kicking to the left at their lower ends, the upper ends of said levers will move to the 80 left. In other words, each of the levers 46^a-46^e is capable of two degrees of motion, but is restrained from movement by unequal pressure in two degrees, cams 57^a-57^e tending to operate said levers in succession, and 85 armature 8 selectively acting to positively lock said levers from motion in the direction of least restraint and compel motion of these levers in a direction of greatest restraint. Therefore, the upper ends of these 90 levers will be kicked to the left in combinations corresponding to the impulses received by the magnet 1.

95 Lugs 56 of the selecting levers are so positioned that cams 57^a-57^e engage them slightly after said cams have passed their horizontal position. These cams are, however, stopped by the escapement in the horizontal position, which position is the middle of lugs 56, and consequently the middle of the 100 sent impulse, so that cams 57^a-57^e do not apparently engage lugs 56 until somewhat after the middle of the sent impulse. But due to the lag in the operation of magnet 1, this actually occurs at about the middle of 105 the impulse. By a proper location of lugs 56 and the slip of the clutch at shaft 23, hereinafter described, it may be brought at any desired point of the impulse. The cams 57^a-57^e of course engage lugs 56 only during a small part of the time occupied in the transmission of a unit impulse, and by being timed so that it occurs in approximately the middle of an impulse, the margin allowable for the mutilation of the signal in its 110 transmission on the line is large as it is only necessary that the impulse shall be good during the interval in which any of the cams 57^a-57^e engages a lug 56.

115 The function of selecting levers 46^a-46^e is to control the setting of a mechanical combination device which in turn controls the setting of the typewheel shaft, and on this setting depends whether a character shall be printed and which character is to be 120 printed, the operations of spacing, lining, returning to the commencement of a new line, and shifting the type wheel from a position to print one set of characters to a position to print another set.

- This combination device comprises, among other parts, a series of tumblers 59^a, 59^b, 59^c, 59^d and 59^e each of which comprises a stem on which is formed a head, shown most clearly in Fig. 21, having two oppositely disposed cams 60 and 61 separated by a recess 62; an upwardly extending lug 63, and a horizontally extending lug 64, the function of which parts will presently appear.
- 10 These tumblers are all carried by an angularly movable frame comprising two side flanges 65 and 66, and webs or plates 67 and 68 connecting these. The stems of all the tumblers rest upon web 67, and are held 15 down thereon by a rod 69 extending across their tops. Each of these tumblers terminates at its rear end in a foot 70 somewhat broader than the stem of the tumbler, and each of these feet extends into a pair of 20 notches or recesses 71, 72 formed in the forward edge of a yoke piece 73 which slips over the web 67 and a horizontal square rock shaft 74 journaled in plates 5 and 6 of the selector casing.
- 25 The parts 68, 73 and 74 are held together by a series of pins 75. These pins serve also as posts to which are attached respectively coil springs 76, one for each tumbler. The other ends of these springs are attached 30 respectively to upwardly extending lugs 77 on the tumblers. These springs at all times exert a pull on the individual tumblers in the direction of shaft 74 so as to hold the lug 64 on each tumbler hard against the 35 forward edge of the web 67. The distance between the inner edge of lugs 64 and the extreme rear end of each tumbler is such that there is a slight clearance between the rear end of the tumblers and the bottom of 40 recesses 71, 72. Each of these tumblers has a normal position of rest from which it is angularly movable in a plane parallel to the web 67, on the yoke 73, as a fulcrum. In Figs. 15 and 22, tumbler 59^a is shown in 45 the shifted position, and the rest of the tumblers in their normal positions.
- For the purpose of locking the tumblers in either of these positions against accidental displacement, the forward edge of 50 web 67 is provided with a series of pairs of indentations 78, 79 (see Figs. 24 and 25), each pair corresponding to the two positions of rest of a tumbler. This locking is effected by the engagement of these indentations with the lugs 63 on the tumbler heads. The web 67 also has on its forward end a series of projections 80 which positively prevent any overthrow of the tumblers in shifting.
- 55 The shifting or setting of these tumblers, above described, is effected by selecting levers 46^a—46^e, and for this purpose each such lever is provided at its upper end with two oppositely disposed cams 81 and 82 (see Fig. 21) adapted to coöperate respec-

tively with cams 60 and 61, on the tumblers, as hereinafter described.

Shaft 74 is rocked so as to bring the tumblers into operative connection with the selecting levers by a bell crank pawl 83 fast 70 on shaft 74 outside of plate 6. The parts which actuate pawl 83 will be described later.

The function of tumblers 59^a—59^e is to interlock by means of lugs 63 with a series 75 of pairs of combination cams 84^a, 84^b, 84^c, 84^d and 84^e, and thus to control the stopping of the type wheel shaft in the desired position.

For each of said tumblers there is one pair 80 of such cams, or ten cams in all for a complete machine. The shapes of these cams are shown most clearly in Fig. 27. In all cases the open part of one cam corresponds to the closed part of its mate. Each cam 85 has half of its circumference high and half low, but the arrangement of these parts is different in each set or pairs of cams. The cams 84^a, for example, are each 180° high and 180° low in extent; cams 84^b have two 90° sections high and two 90° sections low; the cams 84^c, four 45° sections high and four 45° sections low, etc. These cams are all mounted fast on a shaft 85 journaled in plates 5 and 6 and are all so spaced angularly about the 95 axis of said shaft that for any possible combination of said positions of rest of the tumblers, there will be one position and only one where all the lugs 63 on said tumblers will find an opening in all the cams 100 which they engage. The cams 84^a—84^e may assume a variety of shapes different from those shown, so long as they satisfy the above condition. The principle and operation of this combination device is shown in 105 diagram Fig. 3, hereinafter more particularly described.

Mounted fast on the same shaft with cams 84^a—84^e is a ratchet 86 having a tooth for each stopping position of the shaft. This 110 ratchet is adapted to be engaged at times by a pawl 87 on flange 65 of the tumbler frame, and when so engaged holds shaft 86 against rotation.

Plate 6 of the selector casing is screwed 115 flat against the outer edge of a flange 88 formed on a plate 89 secured in an upright position fast to the top of base 90 of the machine. Flange 88 forms a casing for certain parts to be presently described, while 120 plate 89 forms one of the ends of the main frame of the machine, the other end of which comprises a plate 91 made fast in an upright position to the top of the base (see Fig. 1).

The motive power for driving the machine is preferably derived from a small electric motor 92 secured to the rear of the frame of the machine. This motor drives continuously a main power shaft 93, through 130

a pinion 94, a train of reduction gears 95, 96, 97, 98, and a friction clutch. (See Figs. 4, 5 and 6). This friction clutch comprises the gear 98 as the member positively driven from the source of power, a flange or disk 99 for limiting the lateral movement of gear 98 in one direction, a laterally movable friction disk 100 adapted to lie flat against one face of gear 98, a spring 101 forcing disk 100 against gear 98, and said gear against limiting flange 99, and a collar 102 arranged to hold spring 101 under compression and screwed tight on a collar 99' fast on the power shaft. The disk 99 is integral with or rigidly secured to collar 99' and gear 98 is loose on said collar to both rotate thereon and move laterally. Friction disk 100 may move laterally, but is connected positively to said shaft to rotate therewith by pins 103 on collar 99' engaging radial slots 104 in the central opening 105 of said disk. This clutch constitutes a safety device for preventing the breaking of parts by the sudden accidental stopping of the power shaft. With this clutch arrangement, shaft 93 could be suddenly stopped in any position, and the motor would continue to drive gear 98 without transmitting its full power to the driving shaft, due to the slipping of the clutch. Shaft 93, however, is intended to rotate continuously.

Power shaft 93 drives the timing shaft 23 through a friction clutch and coupling shown most clearly in Figs. 55, 56 and 57. This friction clutch comprises a gear 106 as the normally rotating member of the clutch, and this gear meshes with a pinion 107 (see Fig. 2) fast on power shaft 93.

Gear 106 is loose to both rotate and slide laterally on a collar 108 rotatable on a stud 109 fast to end plate 91. One face of this gear lies flat against a disk 110 screwed tight on one end of collar 108. The opposite face of gear 106 is engaged by one face of a friction disk 111 which is laterally movable on collar 108, but which is prevented from rotating thereon by pins 112 on said collar engaging radial slots in the friction disk as in the case of the clutch shown in Fig. 5.

Friction disk 111 is held against the face of gear 106 by a spring 113 held under compression between said disk and a flange 114 integral with collar 108.

In the end of collar 108 is formed a recess 115 and two radial slots 116. (See Figs. 2 and 57). When the selector (parts embraced between side plates 5 and 6) is attached to the machine frame, as described, the head of a male coupling member 117 fast on timing shaft 23 engages recess 115 in the end of collar 108, and two radial arms 118 on this coupling member engage slots 116 of said collar so that positive driving connection is effected between the timing shaft 23 and collar 108, as shown in Fig. 55, which

connection may be severed by simply removing the selector.

Gear 106 rotates continuously while the timing shaft is normally restrained from rotation. As soon as released, however, the timing shaft will take up its rotation from the friction created between gear 106 and friction disks 110, 111 of the clutch.

Gear 106 also meshes with a gear 119 mounted to rotate on a shoulder screw 120 secured to the end of the machine frame (Fig. 2), and this gear in turn meshes with an idler 121 which drives the type wheel shaft 122, through a friction clutch shown most clearly in Fig. 26. This clutch comprises as the normally rotating member thereof, a gear 123 which meshes with pinion 121, and this gear is mounted loosely on a collar 124 fast on the type wheel shaft 122. Gear 123 is adapted to both rotate on collar 124 and move laterally thereof, said lateral motion being limited in one direction by a collar 125 screwed tight on one end of collar 124. Adapted to lie flat up against the other face of gear 123 is a friction disk 126 which is held from rotation on collar 124 by pins 127 engaging slots in disk 126 in a manner similar to that employed in the clutch shown in detail in Fig. 5. Collar 124 is provided at its end opposite collar 125 with a flange 128 between which, and disk 126, a spring 130 is under compression to force disk 126 against the face of gear 123.

Positive driving connection is effected between the type wheel shaft, and shaft 85 carrying the combination disk, by a coupling (see Figs. 28, 29 and 30) comprising a coupling member 129 fast on the type wheel shaft, and a coupling member 130 fast on shaft 85. Member 129 comprises a disk having two flanges 131 separated by slots 132. Member 130 comprises a disk having two lugs 133 adapted to engage with slots 132 in the member 129.

This coupling, like the coupling between the timing shaft and its power shaft, also may be disconnected by merely removing the selector.

The type wheel shaft 122 is square throughout its length, but is mounted to rotate in end plates 89 and 91 of the machine frame by means of collar bearings 134 and 135 fast on said shaft. These bearings are provided with shoulders abutting against plates 89 and 91 and acting to prevent lateral movement of said shaft.

The type wheel 136 is movable longitudinally of shaft 122, and for this purpose is fast on a sleeve 137, having a square bore which makes a sliding fit with the type wheel shaft.

This type wheel, for reasons which will hereinafter more fully appear, is provided with two parallel type flanges, one carrying one set of type, and the other another set.

The paper 138, on which the printing is done, rests upon a supporting plate 139 (see Fig. 4) which forms the top of a casing extending from frame member 89 to 91, and 5 having a curved front 140. The paper is fed into the machine from beneath this casing, passes around the curved portion 140, and thence over the flat portion 139, and is held down at its edges upon said flat portion 10 and guided by plates 141 and 142.

Plate 139 is provided with a transverse slot 143 extending the entire length of the type wheel travel across the machine for permitting a platen, hereinafter described, 15 to strike the paper opposite the desired type.

The paper 138 passes over a series of friction feed rollers 144, 145, 146, fast on a shaft 147 journaled for rotation in the end frames 89 and 91, and the paper is held down upon 20 these rollers by two presser rollers 148, 149, extending entirely across the paper, and rotatably mounted in two pivotally supported arms 150 and 151. Arms 150 and 151 are fast respectively on individual shafts 152, supported in the two end members 89 and 91 of the machine frame, and the presser rollers are held down against the paper under the tension of two coil springs 153 which 25 act upon arms 150 and 151 through arms 154 fast respectively to shafts 152. In the drawings, but one of the shafts 152, springs 153 and arms 154 is shown, it being understood that this construction is merely duplicated at the two ends of the machine.

30 The edge of the type wheel travels between two fork members of a spring presser plate 155 (see Fig. 4) which travels across the paper with the type wheel and holds the paper down in the immediate neighborhood thereof. This presser plate is made fast at one end to a sleeve 156 which is mounted as hereinafter described to travel across the paper with the type wheel.

The type wheel is inked by a felt ink 45 roller 157 mounted on a spindle 158 rotatable in open end slots 159 in a casing 160 which almost completely covers said roller. This construction permits the roller to be readily removed from and inserted in its support. Casing 160 is pivotally mounted 50 between two brackets 161 and 162 formed on the sleeve 156 and the ink roller is held against the type wheel under tension of coil spring 163 (see Fig. 1). Also attached to sleeve 156 is a pointer 164 which is adapted to travel over a scale 165 beneath which the paper passes.

For the purpose of compelling feed roller shaft 147 to stop in a definite position on 60 each step, there is mounted fast on this shaft a correcting wheel 166 having twelve peripheral notches adapted to engage with the pointed nose 167 of a pawl 168 held against said wheel under tension of a spring 169 (see Figs. 38, 39 and 42). Cor-

recting wheel 166 is formed on a collar 170 fast to shaft 147 by pin 171.

Shaft 147 extends through frame 91, and carries on said extension outside said frame a sleeve 172. This sleeve is provided at one 70 end with a flange 173 having therein equally spaced radial slots 174. Adapted to engage with these slots are two pins 175 and 176 carried by a flange 177 on one end of a sleeve 178 slideable longitudinally on shaft 75 147, but connected thereto against rotation thereon by means of a screw 179 having a reduced end 180 which extends into a horizontal slot 181 in shaft 147. Screw 179 also serves to connect sleeve 178 rigidly to a 80 sleeve 182 fitting over sleeve 178 and carrying a knob 183 fast thereon. Sleeve 182 extends beyond the outer end of sleeve 178 where it serves as a chamber for a coil spring 184 carried upon a screw 185 85 screwed into the end of shaft 147. This spring is under compression between the end of sleeve 178 and a washer 186 adjacent the screw head, said spring at all times tending to force sleeve 178 to the left (Fig. 90 38) so as to hold pins 175 and 176 in engagement with two of the slots 174.

The purpose of this construction is to 95 permit the shaft 147 to be disconnected from its power mechanism and operated by hand, which latter is done by pulling the knob 183 to the right and then turning it the desired amount. As long as the knob is in the normal position, sleeve 178 is positively connected to shaft 147 through the 100 clutch members 173, 175, 176, 177, and the engagement of screw 179 with slot 181.

Lateral motion of sleeve 172 on shaft 147 is prevented by a pin 187, on shaft 147, and since the other end of this sleeve abuts 105 against end-plate 91 of the machine frame, sleeve 172 cooperates with wheel 166 to prevent lateral movement of shaft 147 in either direction.

The paper feed shaft 147 is power operated 110 through a ratchet 188 fast on sleeve 172.

The mechanism for operating this ratchet comprises, among other parts, (see Fig. 42) a slide 189 having near one end and on its 115 upper edge a pawl tooth 190 adapted to engage with the teeth of ratchet 188. This slide is mounted for longitudinal movement in two slotted guide supports 191 and 192 extending outward horizontally from 120 end plate 91 of the machine frame to which they are rigidly attached.

Slide 189 is supported at an angle of about 35° from the horizontal, and its lower end rests on support 191 in the bottom 125 of its guide slot. The upper end of this slide, however, rests upon a pin 193, and the edge of the slide which is adapted to engage this pin is cut away as at 194 so as to permit the pawl tooth 190 to clear the 130

ratchet 188 when the slide moves to the right Fig. 42. When at the extreme end of its travel forward or to the left, pin 198 engages an elevated portion 195 of the slide, which jams the tooth 190 against ratchet 188 and prevents overthrow.

Tip 197 of slide 189 engages the periphery of a cam 198 mounted fast on a control shaft 199, and the said tip bears against said cam under the tension of a coil spring 200 attached at one end to a lug 201 on the slide, and to a plate 202 fast to the support 192. A pin 203 fast on slide 189 engages a slot 204 in the lower end of a lever 205 fulcrumed on a pin 206 in a slotted guide 207 fast to the frame plate 91. The upper end of this lever is provided with a nose 208 which is capable of resting against the periphery of a disk 209 or dropping into slots 210 or 211 in the periphery of said disk, depending upon the stopping position of said disk. This disk is fast on and rotates with the type wheel shaft outside of end plate 91.

In Fig. 42 the parts are shown in their positions of rest after the printing of a character.

Control shaft 199 rotates one revolution for each signal received, while the type wheel shaft rotates different fractional parts of a revolution for each different signal and stops in the selected position. Let us assume that the signal received is such that when the type wheel shaft stops, neither of the slots 210 or 211 is opposite the nose of the lever 205. Control shaft 199 will, in such case, make its usual revolution, carrying with it cam 198, and when the drop 198' of this cam passes tip 197 of slide 189, said slide will pass toward the cam under the pull of spring 200, but its movement in this direction is very limited owing to the fact that it is stopped by the engagement of lever nose 208 with the periphery of disk 209. Slide 189 is therefore prevented from passing far enough to the right (Fig. 42) for the pawl tooth 190 to pick up another tooth of its ratchet and when this slide is again returned to its initial position by the cam 198, it does so without rotating the ratchet 188, and, therefore, without affecting the feed roller shaft. If, however, either of the slots 210 or 211 stops opposite lever nose 208, the disk 209 no longer forms an obstruction to the travel of the slide 189 to the right as the drop of cam 198 passes slide tip 197, in which case said slide travels sufficiently in the direction of the cam 198 to allow pawl tooth 190 to pick up another tooth of ratchet 188, and as cam 198 continues its rotation, it will send slide 189 to the left (Fig. 42) causing it to rotate the ratchet 188, and, therefore, the paper feed shaft 147, one step, or the distance from one line to another. In addition to causing slide 189 to travel longitudinally, as described, spring 200 being at-

tached to said slide below its points of support, will cause the ratchet tooth 190 to press against its ratchet 188.

Control shaft 199 is journaled for rotation in the end plates 89 and 91 of the machine, and is held against lateral movement by two collars 212 and 213 fast thereon. (See Figs. 34 and 36.) Rotary motion is imparted to the control shaft from power shaft 93 through pinion 107, gear 106, gear 119, a gear 214 fast to gear 119, a gear 215 (see Fig. 2) and a roller clutch shown in detail in Figs. 34 and 35. This clutch comprises, among other parts, a driving member having a sleeve portion 216 rotatable on shaft 199, and an integral cup shaped portion 217. Gear 215 slips over the outside of the sleeve 216 and is made fast to said driving member by pins 218. Within the cup 217 is a small disk 219 having a hub with a square opening through its center which fits a square end 220 of shaft 199 so as to rotate with said shaft. This disk has four flattened faces 221 on its periphery, and an annular channel 222, the purposes of which will appear later. The hub 223 of disk 219 has a cylindrical periphery on which is mounted a disk 224 rotatable relative to disk 219. This disk 224 has on its face next to disk 219 four segments 225 between which are formed four slots or recesses 226. In each of the recesses 226 is mounted a roller 227 of such diameter that it does not quite fill the space between the inside of the peripheral flange of cup 217 and a flattened face 221 when it is in the center of said flattened face, but large enough so that a slight displacement thereof circumferentially of the clutch will cause it to make contact with both the inside of cup 217 and a flattened face 221 of disk 219.

A spring 228 in channel 222 is connected at one end to disk 219, and at its other end to disk 224, and exerts a tension between these disks such that rollers 227 are always tending to jam between cup 217 and flattened faces 221, but such action is normally prevented by a bell-crank pawl 229 engaging a lug 230 on the periphery of disk 224, which prevents disk 224 from rotating counter-clockwise.

Control shaft 199, and consequently disk 219, are held positively against clockwise movement by a pawl 231 (Figs. 2, 43 and 44) held against cam disk 234 under tension of a coil spring 231' and adapted to engage either of two stop shoulders 232 or 233 on a disk 234 rigidly mounted on the square portion 220 of the control shaft. Therefore, as long as pawl 231 engages either of the shoulders 232 or 233 on disk 234, rollers 227 will be prevented from positively connecting cup 217 and disk 219. The control shaft will therefore at such time normally remain stationary, but cup 217 and gear 215 will continue to rotate under power from shaft 93.

If, however, pawl 229 is disengaged from lug 230, disk 224 will move counter-clockwise under the action of spring 228 until rollers 227 lock cup 217 to disk 219, when 5 the control shaft will rotate with gear 215. This rotation will continue until lug 230 engages an extension 235 on pawl 83, when the 10 rollers 227 will be dislodged from their locking position, and disk 219 will be uncoupled from cup 217 and allow gear 215 to continue to rotate without the control shaft. The square end 220 of the control shaft carries also a disk 236 rotatable therewith and having stop lug 237 which also engages pawl 15 229 and pawl extension 235. The engagement of the lug 237 with the pawl 229 or pawl extension 235 acts as a positive stop for the control shaft to prevent overthrow.

Pawl 229 is operated from the timing 20 shaft by two cam lugs 238 and 239 on the periphery of the flange 114 of the timing shaft coupling, which lugs act upon a beveled nose 240 formed on the end of a lever 241 integral with pawl 229. This pawl is 25 pulled toward disk 224, and nose 240 toward the periphery of disk 114, by a spring 242. The normal position of these parts is shown in Fig. 2.

Also mounted on the square end 220 of the 30 control shaft, for rotation therewith is a cam 243 having a raised portion 244 adapted to engage nose 83' and operate pawl 83 to rock the shaft 74 to set the tumblers as herein-after described. The nose of pawl 83 engages the periphery of cam 243 under the 35 tension of a spring 83". All of the parts of the roller clutch (Fig. 34), the disks 234 and 236, and the cam 243 are held against lateral movement between the frame plate 89 and a 40 washer 245 on the end of shaft 199, the said washer being held in position by a screw 246 on the end of the control shaft.

The printing in this machine is effected by 45 a platen 247 striking the paper opposite the desired type. This platen consists of a block of hard fiber 247 having a cylindrical body 248 held between clamping jaws 249 and 250 forming a head on one end of an arm 251. The body 248 is held friction tight between 50 jaws 249 and 250, the latter of which is made slightly yieldable by means of a slot 252. Arm 251 is integral with a sleeve 253 having a square opening through which passes a square shaft 254 on which the sleeve 253 is 55 longitudinally slidable. This shaft 254 is journaled for rotation in the end plates 89 and 91 of the machine frame. The part comprising sleeve 253, arm 251, jaws 249 and 250, and platen 247 will be hereinafter referred to as the "print hammer".

In this machine the spacing from character to character in a line across the paper is effected by imparting step-by-step lateral motion to both the type wheel and the print

hammer simultaneously. The mechanism 65 for effecting this operation, as well as the printing itself, is shown most clearly in Figs. 47, 50, 51, and 53, to which reference will now be had.

The motion above referred to is imparted 70 to the type wheel through a hollow screw 255, having a peripheral spiral groove 256 adapted to engage with a feather 257 carried by the sleeve 156 which makes a sliding fit with said groove. Feather 257 is held in the 75 groove 256 and connected to sleeve 156 by screw 258. (See Fig. 50).

Lateral motion is transmitted from sleeve 156 to the type wheel through two arms 259 and 260 integral with said sleeve and engaging at their outer ends flanges 261 and 262, respectively, on sleeve hub 137 of the type wheel. Screw 255 is carried by a divided shaft having two sections 263 and 264 in axial alinement. Shaft section 263 is 80 journaled at one end in frame plate 89 of the machine, adjacent which it carries a sleeve 265 fast thereto, as by pin 266. One end of screw 255 is supported upon sleeve 265, but is free to rotate and slide laterally 85 thereon. The other end of shaft section 263 is reduced in diameter to form a spindle 267 which extends into a bore in shaft section 264 which it fits snugly, but loosely enough to permit of relative angular, as well as lateral motion, between the two shaft sections. Shaft section 264 is journaled for rotation in frame plate 91. The end of screw 255 adjacent plate 91 is supported upon a collar 268 on shaft section 264. These parts, however, are all rigidly connected by a pin 269. Carried within screw 255 and on shaft sections 263 and 264 is a coil spring 270 made fast at one end as at 271 to shaft section 263, and at the other end as at 272 to shaft section 100 264.

Lateral motion is imparted to the print 105 hammer through a hollow screw 273 having a spiral groove 274 on its periphery of the same pitch as the groove 256 on the type wheel spacing screw, and carrying a collar 275 slidably longitudinally thereon. Sleeve 275 is provided with a feather which engages groove 274. This latter feather is similar in construction to feather 257 (Fig. 50), and is held in place by a screw 276. Lateral motion is transmitted from sleeve 275 to the print hammer by two arms 277 and 278 on said sleeve engaging respectively with shoulders 279 and 280 on sleeve 110 253 of the print hammer.

The print hammer spacing screw 273 is supported at each end upon collars 281 and 282 on a shaft 283 journaled for rotation in the end frame plates 89 and 91; the screw 273, collars 281 and 282, and shaft 283 all being rigidly connected against relative motion either laterally or angularly by 115 120 125

pins 284 and 285. Sleeves 281 and 282 also serve to prevent lateral motion of shaft 283 by engaging frame plate 89 and 91.

Shafts 264 and 283 are geared together so that they will at all times rotate corresponding amounts and in the same direction. This is effected through a gear 286 fast on shaft 264 meshing with an idler 287 which in turn meshes with a gear 288 fast 10 on a square extension of shaft 283.

From the foregoing construction, it will be seen that when the type wheel and print hammer are once properly aligned and geared, they will remain so. The type 15 wheel may move to any point in a line, and the platen 247 will always be in position to engage with one or the other of the two rows of characters on the type wheel, according to the position of the shift mechanism hereinafter described.

Rotation of screws 255 and 273 is effected by power imparted to shaft 283 through a ratchet 289 fast thereon and coöperating with certain actuating mechanism, which 25 will now be described.

Ratchet 289 is operated for spacing the type wheel and print hammer, by a pawl tooth 290 (see Fig. 47) on a slide 291 mounted for longitudinal reciprocating motion in 30 slotted guide supports 191 and 192, which slide also controls the printing operation in so far as it relates to the movement of the platen toward and away from the type wheel. Slide 291, like the paper feed slide, 35 carries a pin 292 which engages in a slot 293 in the lower end of a lever 294 fulcrumed on pin 206. Lever 294, in the figure shift position, lies in the same vertical plane with a disk 295 mounted on the type 40 wheel shaft for rotation therewith. This disk has upon its periphery six lugs 296, the purpose of which is to coöperate with nose 297 of lever 294, as hereinafter described.

45 The end 298 of slide 291 rests against the periphery of a cam 299, said slide being under tension, in the direction of said cam, of a spring 300 (see Fig. 49) connected to a lug 301 on said slide, and to plate 202, 50 similarly to the spring 200. The other end of slide 291 engages a screw 302 carried by an arm 303 on a collar 304 fast on the print shaft 254, and said screw is held against the end of said slide under the tension of 55 a spring 305 attached at one end to the frame plate 89, and at its other end to an arm 306 on a collar 307 fast to shaft 254.

Cam 299 is adapted to rotate in the same vertical plane in which slide 291 moves, and 60 is mounted fast upon the square end of control shaft 199. When control shaft 199 rotates, as hereinafter described, the drop of cam 299 travels past tip 298 of slide 291, and if the type wheel shaft has not stopped 65 at such position that one of the lugs 296 is

in position to be engaged by nose 297 of lever 294, slide 291 will be pulled quickly in the direction of the control shaft, under the action of spring 300. One effect of this movement of slide 291 is to permit print 70 shaft 254 to be rotated under the action of spring 305 so as to send the platen against the paper. The other effect of this movement of slide 291 is to allow pawl tooth 290 to pick up another tooth on ratchet 289. As 75 cam 299 continues its rotation, slide 291 will be slid to the left (Fig. 47) thus causing pawl tooth 290 to rotate ratchet 289 one step. This rotation of said ratchet rotates spacing 80 screws 255 and 273, which causes the type 85 wheel and print hammer to move one space across the paper. Slide 291, in thus moving, also acts to reset the platen by returning arm 303 to its initial position. A screw 308 in support 191 is adapted to engage the tip of 85 arm 303 on its inward movement, and thus limit the motion of the platen toward the type wheel. This serves the purpose of preventing the printing of adjacent characters when the space signal is received. When 90 this signal is received, the type wheel stops in a predetermined angular position, and the platen advances toward said type wheel as in the printing of a character, but the point on the type wheel which stops opposite the 95 striking position of the platen is cut away, or, in other words, does not contain a type. If, therefore, the motion of the platen toward the type wheel were not limited in such a case, as by screw 308, the platen 100 would not only indent the paper, but would cause an impression by the type on each side of said cut away portion. If the type wheel shaft stops in such a position that any of the lugs 296 on disk 295 is opposite lever 105 nose 297 so as to be engaged thereby, such lug will act as a stop to prevent angular movement of the lever 294 when the drop of cam 299 passes the tip of slide 291, thereby preventing said slide from moving toward the control shaft, and therefore preventing the operation of either the print shaft 254 or the spacing screws 255 and 273.

The nose of lever 294 coöperates either with disk 295 as described, or with a disk 115 309, according to the state of certain type wheel shift mechanism hereinafter more particularly described. Disk 309 is provided with three peripheral lugs 310 adapted to coöperate with the nose 297 of lever 294 in a 120 manner similar to the lugs 296 on disk 295. Disks 295 and 309 are mounted on the type wheel shaft 122 for rotation therewith, but are slidable laterally on said shaft together as hereinafter more particularly described.

125 The stepping of the ratchet 289 forward, as described, not only steps the type wheel and print hammer across the paper, through the rotation of screws 255 and 273, but it also winds up spring 270 (Fig. 50), which 130

places the ratchet 289 under tension tending to rotate backward. This backward rotation of said ratchet, however, is normally prevented by tooth 311 of a holding pawl 312 mounted in guide slots in supports 191 and 192. Movement of slide 312, however, in the direction of support 192 is limited by shoulder 313 on said slide engaging said support. This pawl 312 is at all times under tension of a spring 314 attached at one end to a lug 315 on pawl 312, and at its other end to plate 202, said spring at all times tending to pull said pawl in the direction of the teeth of said ratchet.

While spring 270 is wound up by the action of ratchet 289, it is always under a certain amount of torsional tension, which can be regulated by turning shaft section 263. This shaft section, however, is normally held against rotation by a latch 263' engaging a square portion 263" of said shaft section.

The return of the type wheel and the print hammer to the commencement of a line is effected by releasing pawls 290 and 311, which permits the spring 270 to unwind and thereby rotate screws 255 and 273 backward. The mechanism for thus releasing ratchet 289 comprises, among other parts, a slide 316 mounted for longitudinal reciprocating motion in guide slots in supports 191 and 192. One end of slide 316 extends through support 192 and engages the periphery of a cam 317 fast on control shaft 199. The tip of this slide is held against cam 317 under the tension of a spring 318 secured at one end to a lug 319 on slide 316, and to plate 202. This slide carries a pin 320 which engages a slot 321 in the lower end of a lever 322 fulcrumed on pin 206 and provided with a nose 323 adapted to coöperate, in the figure shift position of the type wheel, as herein-after described, with a disk 324 fast on the type wheel shaft 122, and provided with two peripheral notches 325 and 326 (see Figs. 33 and 47).

Slide 316 is provided with an arm 327 extending at right angles therefrom and passing underneath pawl 312, slide 291, and a pawl 328 to be presently described. The end of slide 316 adjacent arm 327 is beveled as at 329 where it coöperates with a lug 330 on a slide 331 held flat against the outer face of support 191 by shoulder screws 332 which pass through slots 333 (see Fig. 51) in said slide so as to permit the slide to move laterally on said screws. Slide 331 is under tension to the right, when viewing the machine from the front, of a spring 334, but the movement of said slide to the right is normally prevented by the engagement of lug 330 with slide 316.

When the signal is received to return the type wheel and print hammer to the commencement of a new line, type wheel shaft

122 will stop in such a position that notch 325 on disk 324 will register with nose 323 of lever 322, and when control shaft 199 rotates for this signal, slide 316 will travel toward the axis of control shaft 199 as the drop of cam 317 passes the tip of this slide, since the nose 323 of lever 322 will pass into notch 325. If notch 325 were not opposite nose 323, said nose would engage the periphery of disk 324 and thereby prevent said movement of slide 316. When slide 316 thus moves toward the control shaft, its beveled end 329 is removed from the path of lug 330 on slide 331, which permits said slide to be pulled to the right under the action of spring 334. As control cam 317 continues its rotation, however, slide 316 will be moved thereby in the opposite direction to its former movement, causing beveled end 329 of said slide to ride up on lug 330 of slide 331. The effect of this is to raise arm 327, which in turn lifts pawl teeth 311, 290 and 343 out of the path of ratchet 289, thereby setting said ratchet free to rotate backward, which rotation takes place under the action of spring 270, as hereinbefore described, and returns the type wheel and print hammer to the commencement of a new line.

When the said type wheel and print hammer reach the end of their travel back, sleeve 253 of the print hammer strikes an arm 335 fast on a laterally movable shaft 336. This shaft also carries fast thereon an arm 337 which is adapted to engage a shoulder 338 on an extension 339 of slide 331. When sleeve 253 strikes arm 335, shaft 336 will be shifted to the left, carrying with it arm 337 which, engaging shoulder 338, will return slide 331 to its normal position, thereby lowering slide 316, which will permit the pawl teeth 311, 290 and 343 to return to their normal positions with relation to ratchet 289.

The pawl 328 and the shallow notch 326 in disk 324 are for the purpose of "back spacing", by which is meant the stepping of the type wheel and print hammer back one space at a time in the direction of the commencement of a line. This is useful for the purpose of correcting errors.

Pawl 328 is mounted in guide slots in supports 191 and 192, and is at all times under tension of a spring 340 tending to pull it down in the direction of ratchet 289, said spring being connected at one end to a lug 341 on said pawl, and at its other end to plate 202. The movement of pawl 328, in the direction of support 192, is limited by a shoulder 342 on said slide. This pawl is provided with a tooth 343 which is normally held out of engagement with ratchet 289 by an elevated portion 344 of said pawl resting upon the arm 327 of slide 316. Pawl 312 and slide 291, however, are not normally raised by the arm 327, since said arm reg-

- isters with recesses 345 and 346 (Fig. 49) which permits their pawl teeth to normally engage ratchet 289. Pawl 328 is also provided with a recess 347, but this recess is not in alinement with recesses 345 and 346. It will also be observed that tooth 343 on pawl 328 is slightly in advance of the pawl tooth 311 and 290, as indicated by the dotted line 348, Fig. 49.
- 10 When the space back signal is received, shallow notch 326 of disk 324 will stop in front of nose 323 of lever 322, and as control cam 317 rotates for this signal, slide 316 will move in the direction of the axis of the 15 control shaft, as hereinbefore described, but its movement will be limited, owing to the shallow depth of the notch 326. Slide 316 will only move at this time the distance between dotted lines 349 and 350 Fig. 49.
- 20 This movement, however, is sufficient to cause arm 327 to clear shoulder 344 of pawl 328, (see Fig. 49) the said arm passing into the recess 347 of pawl 328, permitting said pawl to descend and thereby send its tooth 25 343 into the path of the teeth of ratchet 289. When slide 316 travels in the direction of control shaft 199 for the back space signal, arm 327 of said slide will engage cam shoulders 351 and 352, thereby removing pawl 30 teeth 311 and 290 from engagement with ratchet 289, which being thus released rotates backward under the action of spring 270 until its tooth formerly engaged by pawls 311 and 290 comes into engagement 35 with tooth 343 of pawl 328. As cam 317 continues its rotation, slide 316 will be moved to the left (Fig. 47) causing its arm 327 to raise pawl 328 by engaging the cam face of elevation 344 (Fig. 49). The 40 ratchet 289 will therefore be released and rotate backward the distance of one tooth when it will be stopped by the pawl teeth 311 and 290, thus allowing spacing screws 255 and 273 to rotate backward a sufficient 45 amount to cause the type wheel and print hammer to step back one space. It should be noted that the beveled end 329 of slide 316 is of such length that when the nose of lever 322 engages shallow notch 326 in disk 50 324, slide 331 cannot move to the right.
- Lever 322 is adapted to coöperate either with disk 324, as described, to effect the return of the type wheel and print arm to the commencement of a line, or with a disk 55 353 for the same purpose, depending upon the state of the type wheel shift mechanism hereinafter described. Disk 353 is mounted on the type wheel shaft 122 to rotate therewith, and is provided with a notch 354 in permanent alinement with notch 325 of disk 324, which performs a corresponding function to notch 325 with respect to the nose 323 of lever 322. Disk 353, however, is not provided with a notch corresponding to 60 notch 326 of disk 324. The disk 324 co-

operates with lever 322 only in the figure shift position of the type wheel. The operation of spacing back, therefore, may be performed only in the figure shift position of the type wheel.

The machine herein shown is designed to operate with a five unit code, hereinafter more particularly described. With such code it is possible to get only thirty two combinations, which is not enough usually for a printing telegraph. In using such code, it is therefore desirable to have a double type wheel, and shift from one set of characters to another. By such an arrangement, the number of available combinations may be increased to sixty four, with a five unit code. The type wheel in this machine is therefore provided with two parallel rows of type, one of said rows containing the alphabet and certain other characters, and the other row containing numerals and certain other characters, as shown most clearly in Figs. 31 and 32. Mechanism is therefore provided to shift the type wheel bodily longitudinally of its shaft so that either of these rows of type may be brought into alinement with the printing platen. This shifting of the type wheel is effected by moving the spacing screw 255 longitudinally, and this in turn is effected by imparting longitudinal motion to the spacing screw shaft section 264. In thus shifting the type wheel, it is necessary also to shift disks 295, 309, 324 and 353, and for this purpose all of these disks are coupled rigidly together, so that they may all move together longitudinally of their supporting shaft 122. The figure shift mechanism comprises, among other parts, (see Figs. 58 to 62) a slide 355 mounted for reciprocating motion longitudinally in guide supports 191 and 192, one end of which slide is normally held in engagement with the periphery of a cam 356, fast on control shaft 199, said slide being held against said cam under the tension of a spring 357 so disposed as to pull also upward on said slide for purposes which will later more fully appear. This slide carries a pin 358 which engages a slot 359 in the lower end of a lever 360 fulcrumed on pin 206, and having a nose 361 adapted to coöperate, as hereinafter described, with a disk 362 fast on the type wheel shaft. Disk 362 is provided with a peripheral notch 363 which when the figure shift signal is received is adapted to register with nose 361 of lever 360, and permit the said nose to engage the same when the control disk 356 is rotated to such a position as to allow slide 355 to be pulled in the direction of the control shaft by spring 357. When the type wheel is in the letter shift position, a lip 364 on an arm 365 rests upon an elevated portion 366 of slide 355. This arm is made fast at one end to a square shaft 367, mounted for ro-

tation in brackets 368 and 369. Fast to this shaft are two arms 370 and 371 which are provided respectively with pins 372 and 373 which engage with two annular flanges 374 on a collar 375, fast on an extension of the spacing screw shaft member 264.

When slide 355 travels toward control shaft 199 on the reception of a figure shift signal, lip 364 will drop into a depression 376 in the slide 355. As control shaft 199 continues its rotation, however, slide 355 is caused to travel in a direction away from the control shaft, or to the left in Fig. 58, and in doing so the lip 364 will be engaged by the shoulder formed by the elevated portion 366 of slide 355, and as this slide continues its motion to the left, Fig. 58, angular movement will be imparted to the arm 365, which will rotate shaft 367. The effect of this is to cause arms 370 and 371, acting through pins 372 and 373 and the collar 375, to shift the type wheel spacing screw and the type wheel to the dotted line positions shown in Fig. 62, which is the figure shift position of the type wheel. At the same time disks 295, 309, 324, and 353 will be shifted laterally of the type wheel shaft so as to bring disk 295 and 324 into alignment with the noses of levers 294 and 322, respectively. For the purpose of thus shifting these disks, there is made fast to shaft 367, two arms 377 and 377' carrying respectively rollers 378 and 378' which rest between disk 295 and a disk 329, the latter disk being slideable longitudinally of shaft 122, and rigidly connected to disks 295, 309, 324 and 353. Arm 377' is really an extension of arm 370 (see Figs. 45, 46 and 58).

When slide 355 reaches the end of its travel to the left (Fig. 58) a projection 380 on said slide engages with an arm 381 fast to the end plate 91 of the machine, (see Figs. 61 and 46) and holds the type wheel and control disks in the shifted position against the tension of a spring 382 fast at one end to arm 371, and at its other end to bracket 369 until released, as hereinafter described.

For the purpose of shifting to letters, there is provided, among other parts, a slide 383 mounted for longitudinal movement in guide slots in supports 191 and 192. One end of this slide is adapted to engage the periphery of a cam 384 fast on control shaft 199, and is held against said cam under the tension of a spring 385. This slide carries a pin 386 which engages a slot 387 in the lower end of lever 388 fulcrumed on pin 206 in guide block 207. Lever 388 is provided with a nose 389 which is adapted to cooperate with disk 390 fast on type wheel shaft 122. Disk 390 is provided with a peripheral notch 391 which, when the letter shift signal is received, stops in front of nose 389 of lever 388. Then, when cam 384 is rotated

to that point where its drop passes the end of slide 383, said slide will be pulled toward the control shaft by spring 385, the nose of lever 388 entering notch 391. When slide 383 travels as above stated, a horizontal projection 392 on said slide will engage a beveled lug 393 on slide 355, and in doing so will depress the latter slide so that projection 380 thereon will be released from arm 381, and lip 364 disengaged from notch 376, thereby permitting spring 382 to rotate shaft 367 in such direction as to shift the type wheel and control disks to the full line position shown in Fig. 62.

All of cams 198, 356, 384, 317 and 299 are mounted on the control shaft to rotate therewith, and for this purpose each cam has a central opening through it adapted to engage the square portion of the control shaft, but all such cams are rigidly held on said shaft against movement laterally thereof, since it is not necessary to shift any of these cams, as in the case of certain of the control disks.

It will be noted from Fig. 37, which shows most clearly the relative angular positions of control cams 198, 356, 384, 317 and 299, that cams 356 and 384 are spaced 90° behind the other cams of that group. This is done in order to cause the type wheel shift operations to take place at different times from the other operations. If the two occurred at the same time, lever noses 297 and 323 (Fig. 47) could in certain positions jam against the projections on their control disks. By arranging the control cams as noted, the actual shifting from letters to figures does not take place until the first signal in the figure shift is received, but it shifts before the character corresponding to the signal is printed.

Since the motion of spacing is a positive motion, some means must be provided to prevent jamming at the end of a line. For this purpose there is provided, among other parts, a lever 394 fulcrumed upon shoulder screw 395 on support 191. (See Figs. 52 and 53.) Lever 394 has a cam tip 396 which normally rests upon the upper edge of a beveled portion 397 of arm 337. Lever 394 is provided at its other end with a projection 398 adapted to engage the under face of spacing slide 291 under the tension of spring 399 tending to rotate said lever in such a direction as to disengage the pawl tooth of spacing slide 291 from ratchet 289, but is normally prevented from doing so by the tip 396 engaging arm 337. (See Figs. 52 and 53.) When, however, the type wheel and print hammer reach the extreme end of their travel to the right, the sleeve 253 of the print hammer will strike an arm 337 fast on shaft 336 with arm 337, and this will push arm 337 to the right, Fig. 53, disengaging portion 397 of said arm from the high

part of tip 396 of the lever 394, allowing said lever to rotate under the action of spring 399, when the projection 398 on said lever will raise spacing slide 291. As long as this is the case, ratchet 289 will not be moved, but as the type wheel and print hammer take up their travel to the left or toward the commencement of a new line, shaft 336 will be returned to its normal position, under the action of a spring 400 rigidly attached at one end to the end frame 89 of the machine and engaging a pin 401 on shaft 336. Shaft 336 in thus returning to its normal position, in which case it travels to the left, Fig. 53, causes the tip 396 of lever 394 to ride up on the beveled face 397 of arm 337 and return to its initial position on the upper edge of said arm, thereby releasing the spacing slide 291 and allowing it to return to its normal position.

Spring 400 is backed up by a rigid support 402 which prevents it from moving shaft 336 too far. Another spring 403 on the opposite side of support 402 retains shaft 336 normally in a fixed position, but capable of being moved longitudinally in either direction.

The control mechanism, located outside of plate 6, at the left hand end of the machine (Fig. 1), is inclosed in a casing 404 which is supported upon said plate and a spider 405 (Fig. 45). This spider also receives the ends of the control shaft, type wheel shaft, the return shaft and others extending beyond plate 6.

I do not wish to be understood as limiting this invention to any special code of signals, nor method of nor apparatus for transmitting the current to effect the operation of my improved receiver, nor to any special character of current; but the specific machine here shown was designed to operate with a particular character of signal, and for the purposes of describing the operation of the present machine, brief reference will now be had to the signals themselves.

This system of signals contemplates the allotment to all the signals equal time intervals, each of which we will call a signal period. Such signal periods correspond to the time of a half revolution of the timing shaft in the present machine. It further contemplates the division of each signal period into six equal unit impulse periods. This will all be better understood by reference to the current diagram Fig. 63 in which two successive signals are indicated. In this diagram the horizontal dotted line O—O represents the line of zero current, and the spaces between adjacent vertical dotted lines indicated S, A, B, C, D and E, represent the unit impulse periods.

The spaces indicated S correspond to the intervals of the starting impulses, and the spaces A B C D and E, the intervals of the

five unit signal impulses which are employed in various combinations to form the signals proper. At the commencement of each signal period an impulse is transmitted to start the receiver into operation, and the character of the signal will depend upon whether an impulse is transmitted which corresponds to the A, B, C, D, or E period or any combination of these. With five such unit impulse periods, thirty two such combinations may be obtained. But by employing a double type wheel and shifting, these combinations may be duplicated for different signals, thereby increasing the effective number to sixty four. When a signal involves two or more adjacent impulses, these merge into one, so that if a signal involves the A impulse period, for example, the starting impulse is not in fact a separate impulse, but merges into the A impulse; if it involves the A, B, C, D and E impulses, these all merge into one single impulse.

In the diagram (Fig. 63) the signal on the left is formed by the B C combination, and the signal on the right by the A B C D and E combination.

Since the apparatus is independent of the strength and polarity of these impulses, the matter of their relative strength or polarity may be disregarded. We may therefore consider all the impulses as of the same strength and polarity.

The spaces between successive signals indicated L, represent intervals of lag which are automatically created when the transmitter is operating at maximum speed. When the transmitter is not operated at maximum speed, longer periods of lag will occur between successive signals, due to the natural pauses of the operator.

A period of lag between successive signals is desirable in order to prevent any signal from blending with the starting impulse of a succeeding signal. This, however, is a matter which has to do more especially with the transmitting apparatus which forms no part of my present invention.

The actual operation of the machine from the reception of the starting impulse to the printing of a character, will now be described, in which it will be assumed that the signal received is that shown on the left in Fig. 63, or the one involving the B C combination. In the letter shift position of the type wheel, this will print the letter "I", and in the figure shift position will print the numeral "8".

Motor 92 operates continuously, and through the train of gearing hereinbefore described continuously drives power shaft 123, 93, through which gears 106, 119, 121, 123, 214 and 215 (Figs. 2 and 4) are kept in continuous motion. The timing shaft 23, type wheel shaft 122, control shaft 109, as well as balance shaft 15 and shaft 85 are nor-

mally restrained from rotation, as hereinbefore described, but when released take up rotation from their respective clutches.

Let it be assumed that magnet 1 is connected in a line over which this signal is transmitted.

The reception of the starting impulse energizes magnet 1 and causes it to draw up its armature. (See Fig. 7.) When this takes place, said armature will engage the tip of arm 39, and acting therethrough will raise slide 30 so as to remove its nose from the path of stop 35 on balance 14, thus setting said balance free to oscillate. Directly 15 after this happens cam 38' raises the nose of lever arm 44, which, acting through lever 43 and yoke 42 swings arm 39 clear of armature 8. (See Fig. 9.)

The balance being thus free will continue 20 its oscillation under the action of the escape mechanism (Figs. 15, 19 and 20) through power received from gear 106 through the friction clutch of which this gear forms a part. Timing shaft 23 will thus rotate 25 step-by-step for one-half revolution, when it will be automatically stopped by the entrance of the nose of stop slide 30 again into the path of balance stop 35, caused by the engagement of the nose of arm 37 on said 30 stop slide with a recess 38^a of cam 38 which rotates with the timing shaft. Also at the end of this half revolution of shaft 23, the nose of arm 44 drops into one of the notches 38^b in cam 38', thus allowing lever 43 to 35 return pivoted arm 39 to its normal position.

This rotation of the timing shaft 23 causes 40 cams 57^a—57^b to successively engage lugs 56 on levers 46^a—46^b, the times of the engagement of said cams with said levers corresponding respectively to the five impulse periods A B C D and E of a signal period. If these cams were thus set in rotation, and 45 no signal impulses received after the starting impulse, levers 46^a—46^b would be successively kicked to the left, Fig. 13, at their bottoms, while their upper portions would remain against guide support 31, under the action of springs 55. If, however, at the 50 time that any of the cams 57^a—57^b engage their corresponding levers 46^a—46^b, armature 8 happens to be in its up position in front of the feet 47 of these levers, said feet will be restrained from movement to the 55 left, while the upper ends of said levers will move to the left, as shown in Fig. 14. We are now assuming that the signal transmitted is formed by an impulse occupying the B and C code positions. This being the case 60 magnet 1 will be energized at the time that cams 57^a and 57^b operate upon their corresponding levers 46^a and 46^b. The result is that the upper ends of these levers will be kicked to the left as shown in Fig. 14. When 65 in this position, the lugs 49 on these levers

are withdrawn from beneath their pawls 52 which, under the action of springs 54, assume the position shown in Fig. 14, in which they lock the levers 46^a and 46^b in the set position.

Just before the timing shaft reaches the end of its half revolution, above referred to, cam 239 on disk 114 engages nose 240 on lever 241, assuming that the machine is started into operation from the position of these parts shown in Fig. 2. When nose 240 is so engaged, lever 241 is caused to move on its pivot and to lift pawl 229 from engagement with lugs 230 and 237 of disks 224 and 236, respectively. These disks being 70 thus released, permit control shaft 199 to start into rotation through the action of its friction clutch heretofore described. The elevated portion 244 of cam 243 (see Fig. 16) immediately after the control shaft 75 starts into rotation, operates upon the nose 83^a of pawl 83, so as to rotate said pawl and shaft 74 in a counter-clockwise direction. The effect of this is to impart angular movement to the frame carrying the tumblers 59^a—59^b, about the axis of shaft 74, said frame carrying with it all of said tumblers. This downward movement of the tumblers causes the engagement of cams 60 on tumblers 59^a and 59^b with cams 81 (see Fig. 14) 80 of the set combination levers 46^a and 46^b. The effect of the engagement of these cams 85 60 and 81 is to shift tumblers 59^a and 59^b from their normal positions to their set positions, which, as hereinbefore described, is 90 from a notch 78 to an adjacent notch 79 in the end of the tumbler frame.

In Fig. 22, the tumbler 59^a is shown in 95 its normal position, and the other tumblers in their set positions for the signal previously received.

The downward movement of the tumblers, as above described, also serves to return the tumblers set by the preceding signal to their 105 normal positions. This is effected by the engagement of cams 61 on the tumblers with cams 82 on those of the selecting levers 46^a—46^b, which are not set for the particular signal now being received.

Another effect of the above described angular movement of the tumbler frame is to 110 remove holding pawl 87 from engagement with ratchet 86 on the shaft which carries the combination disks 84^a—84^b. The effect of this is to release shaft 85 and permit it to 115 take up rotation from gear 130 through its friction clutch (Fig. 26), thus setting the type wheel shaft into rotation, as well as shaft 85, these two shafts being positively coupled, as hereinbefore described.

Still another effect of the downward movement of the tumbler frame is the releasing 120 of locking pawls 52, by the engagement of said frame with the ends 52' of said pawls, near the end of said downward movement. 130

When this occurs, the forward end of each of said locking pawls is raised against the tension of its spring 54 out of the path of lug 49 of each receiving lever 46^a—46^b, thus allowing the set levers 46^a—46^b to return to normal.

As the control shaft continues its rotation, the elevated portion of cam 243 will pass by the nose 83' of pawl 83, which will permit 10 said nose to be drawn quickly toward the axis of shaft 220, under the action of spring 83''. The effect of this will be to rotate shaft 74 in a clockwise direction, Fig. 16, which brings lugs 63 of the tumblers into engagement with the peripheries of the combination disks 84^a—84^b.

It should be stated, however, that when shaft 74 was rocked in an anti-clockwise direction, by the elevated portion 244 of cam 20 243, extension 235 on said pawl was brought into the path of lugs 230 and 237 on disks 224 and 236, whereby the rotation of the control shaft is momentarily stopped, the parts being in the position shown in Fig. 17.

Shaft 85, however, continues its rotation 25 until it has reached such an angular position that there is an opening formed by the combination disks 84^a—84^b into which the lugs 63 of all the tumblers may simultaneously 30 enter. When this angular position is reached, the tumblers thus enter said openings under the action of spring 83'', permitting the tumbler frame to move in a clockwise direction with shaft 74 and causing 35 stop pawl 87 to engage ratchet 86, and stop the rotation of shaft 85. This causes the stopping of the type wheel in the desired angular position to print the required character. The ratchet 86 is provided with sixty- 40 four equally spaced teeth or one tooth for each combination or stopping position of the type wheel shaft.

The rotation of shaft 74 caused by the entrance of tumbler lugs 63 into their combination 45 openings also causes the withdrawal of stop 235 (Fig. 17) from the path of lugs 230 and 237, thus setting control shaft free to rotate until said lugs again engage pawl 229, when the control shaft will be brought 50 to a permanent stop for this signal.

The setting of the type wheel, as described, also acts to set the disks 295 and 309 in the proper angular position to coöperate with the nose 297, according to whether the type wheel 55 is in the letter shift or figure shift position, as described, said nose acting through lever 294 to control the printing and spacing slide 291 for effecting the printing and spacing, as hereinbefore fully described.

The operations of feeding the paper, spacing 60 alone, back spacing, returning to the commencement of a new line, and shifting the type wheel from letters to numerals, or vice versa, all depend upon the angular position in which the type wheel shaft is stopped,

and so far as the selector mechanism is concerned, the operation of this is the same for performing these operations as for printing a character.

The operation of the immediate mechanism 70 for performing these various functions has been already described, so need not here be repeated.

The principle and operation of the combination device comprising permutation 75 disks 84^a—84^b and tumblers 59^a—59^c is clearly brought out in the diagram Fig. 3, which may also be considered a key to the combinations.

In this diagram the pairs of elongated 80 rectangles embraced between the brackets 84^a—84^b represent in development the various pairs of disks similarly numbered in the mechanical views, while the small rectangles 59^a—59^c represent the five tumblers. The 85 black portions of the developed disks represent the depressions and the white portions the elevations thereof.

The spaces between the vertical dotted lines represent the various stopping positions of the disks, corresponding to the recordable characters located along the upper portion of the diagram, and the stopping positions of the disks for effecting the operations of back spacing, returning to the commencement of a line, figure shift, lining, spacing, and letter shift, are represented respectively by BS, BK, FS, LI, SP and LS.

The dotted line rectangles adjacent the rectangles 59^a—59^c represent the normal 100 positions of the tumblers, and the full line rectangles, the set position thereof. According to the combinations here shown all of these tumblers occupy the dotted line positions at one time for the lining operation, 105 and for the figure shift they all occupy the full line positions shown.

Let it be assumed that a signal for the figure shift is received. In this case the tumblers all occupy the full line positions 110 59^a—59^c. Now if we bring these rectangles to the position on the developed combination disks indicated FS, it will be seen that each tumbler will register with a black portion of the disk. Therefore when the combination disks rotate so as to establish this relation between the disks and tumblers, the lugs 63 on all the tumblers find openings which they enter, and by doing so permit the pawl 87 (see Fig. 16) to engage ratchet 86 115 and stop the type wheel shaft in the desired angular position to effect the figure shift. The figure shift having been operated, let it now be assumed that the numeral "7" is to be printed. This numeral calls for the 12 a b c combination. In such a case the tumblers 59^a, 59^b and 59^c would occupy the full line positions shown by the rectangles correspondingly numbered on the right of the diagram (Fig. 3), but the tumblers 59^a and 13

59^a would occupy the dotted line or normal positions. Now then, if the rectangles indicating the tumblers in these positions be placed in the space below the numeral "7," 5 it will be seen that all said rectangles will register with black portions indicating depressions in the combination disks. In the letter shift position of the type wheel this same combination will print the letter U. 10 The combinations employed for the various signals are shown by the small letters at the bottom of the diagram. These letters correspond to the exponents used with the reference numerals to indicate the selector 15 levers and their operating cams, the combination disks, and the tumblers, as well as the five impulse periods of a signal period. For example, the signal for the letter M, or the question mark, is composed of 20 impulses occupying the c, d and e impulse positions and effects the setting of selector levers 57^a, 57^b and 57^c, and tumblers 59^a, 59^b and 59^c.

Reference will now be had again to arm 25 39 and its coöperating parts. (See Figs. 7, 8 and 9.)

The shifting of this arm to the position shown in Fig. 9 effects two very important results. One is that it prevents the stop 30 slide 30 from being held up too long, owing to the lag of the magnet 1, and the other is that it makes possible the use of the machine on a closed circuit including a source of voltage.

35 Since the action of magnet 1 lags behind the current, its armature will remain up after the actual ending of the final impulse for a signal. If the signal involves the E impulse position (see Fig. 63), the current 40 for that signal lasts almost until the timing shaft comes to rest. Therefore, if the lower end of arm 39 remained above armature 8, there is a possibility that slide 30 might not drop in time to stop the balance 14 at the 45 proper instant. By providing means for automatically shifting the arm 39 to the position shown in Fig. 9, the stop slide 30 can drop at the end of a signal notwithstanding the armature 8 may remain up.

50 The operation of arm 39 in the manner described also renders possible the operation of the machine on a closed circuit such, for example, as shown in Fig. 64. This diagram shows two stations, at each of which 55 is located one of my receivers indicated by the magnets 1, connected in series in a line circuit normally closed through switches 406, each of which is in parallel with a transmitting contact 407. The signaling 60 current is derived from a source 408. Such an arrangement shows a substitution of my receivers for Morse sounders, and the substitution of transmitting contacts 407 for Morse keys in the usual American closed 65 circuit method of operating Morse circuits.

According to this method of operation, whenever one of the transmitters is not working, its switch 406 is closed, so that normally the line circuit is closed and current flows through magnets 1. When the 70 circuit becomes thus closed through either of the magnets 1, the armature of that magnet will assume the position shown in Fig. 9, and will remain in that position as long as the line circuit remains closed. The effect of this will be to operate the figure shaft mechanism of the printer, but since the arm 39 is drawn to the position shown in Fig. 9, stop slide 30 drops into position at the 75 end of that signal to stop balance 14, so that notwithstanding the armature 8 is up, the machine will not continue to operate. On the other hand, if the slide 30 remains up as long as does the armature 8, the machine would operate the figure shift mechanism 80 continuously at regular intervals.

The operation of the figure shift once on the closure of switch 406, however, does no harm, since whenever the machines are started it is always necessary to insure that 90 their type wheels are in the letter shift position. This is done by first shifting to figures and then to letters. The operator would not immediately shift to letters, since if the machine were already in the letter shift position, a comma would be printed, but by first shifting to figures and then to letters, nothing is printed.

Fig. 65 shows the connections for three stations on a way wire in which three of my 100 receivers are connected. This arrangement is known as the British open circuit method, in which case the line is normally closed, but at this time there is no voltage on the line. This method requires a battery 409 105 at each station, which is thrown on to line in series with magnets 1 and transmitter contacts 410 each time one of said contacts is operated. As current only traverses magnets 1 in this case during actual transmission, the operation of the arm 39, Fig. 7, as described with relation to Fig. 64, is not essential. In such a case the arm 39 could be fixed rigidly to the slide 30, but for reasons hereinbefore pointed out it is preferable 110 to have the arm 39 operate as described, aside from the question of using the machine on a closed circuit.

115 So far as the operation of the transmitter contacts 407 or 410 are concerned, these may 120 be operated in any desired way, preferably by the transmitting mechanism described and set forth in my pending United States application Serial No. 794,633.

125 For the purposes of illustration, however, I have shown in Fig. 66 in diagram one arrangement which may be employed for operating these contacts to send signals of the character herein described. In this diagram, 411 represents a magnet for operating con- 130

tact 407. This magnet is permanently in series between a collector ring 412 and one terminal 413 of a source of local direct current. Associated with collector ring 412 is a commutator 414, and adapted to sweep collector ring 412 and commutator 414 are two brushes 415 and 416, respectively, which are in permanent electrical connection. These brushes are both driven from a common driving member represented as a disk 417 fast on a collar 418 which is rotatable on a shaft 419. Shaft 419 is constantly driven through gears 420 and 421 from an electric motor 422, which may be provided with any suitable means for steadyng its motion. Slidable longitudinally on collar 418, but rotatable therewith is a friction disk 423 which is held against one face of gear 420 under the tension of spring 424. Gear 420 rotates continuously, but friction disk 423 and driving disk 417 are normally held from rotation by a pivoted stop 425 engaging a pin 426 on disk 417. This pivoted stop is operated by a magnet 427 which in turn is operated by relay 428 under the control of a series of five movable contacts 429 which control five branch circuits connected respectively to five of the segments of commutator 414.

80 The operation is as follows: When any of the contacts 429 is operated, it completes a circuit through its fixed contact 430, forward coil of relay 428, the top segment of commutator 414, brushes 415 and 416, and magnet 411. The effect of this is to cause magnet 411 to operate contact 407, and at the same time to cause relay 428 to close a circuit through magnet 427, which latter magnet operates upon pivoted stop 425 to free the pin 426, whereupon disk 417 will start into rotation from power received through its friction clutch. Then as brush 416 passes over the segment of the commutator connected to the fixed contact 431 of the operated contact 429 another impulse will be sent through magnet 411 which will cause it to again operate contact 407. The first impulse sent on the operation of each contact 429 through contacts 430 is the starting hereinbefore referred to. The impulses sent to magnet 411 through contacts 431 are the regular signal impulses which are sent in various combinations for each signal, the signals being formed by operating the contacts 429 in various combinations. There are many ways of operating these contacts in combinations well known in the art, so that it is unnecessary to further go into this phase of the matter here. One way of doing this is shown in my British Patent No. 15,167 of 1909.

At the end of a complete revolution, the brushes 415 and 416 are stopped in the position shown, by the engagement of pin 426 with pivoted stop 425.

The tongue of relay 428 is returned to its normal position on each operation thereof by the engagement of contact 432 with contact 433 which energizes the back coil of relay 428.

70 The bottom or disconnected segment of commutator 414 is for the purpose of creating the interval of lag between successive signals.

75 Nothing new is here claimed for this specific transmitting arrangement, it being shown merely for the purposes of illustrating one way of selectively operating contacts 407 or 410, and is adapted here mainly for the reason that it is easy to show in a diagram.

It should be understood, however, that my improved receiver is not limited to any special kind of transmitter.

80 It will be seen from the foregoing description that the operation of this machine is almost wholly mechanical, the only electrical part being the magnet 1, which initially controls the entire machine.

85 It will also be observed that in the machine here shown all of the operations of printing, spacing, back spacing, shifting of the type wheel, lining and returning to the commencement of a line, are controlled by the stopping of the type wheel shaft, and 90 also that the type wheel passes from one printing position to the next by a continuous motion, by which much time in operation is saved as compared with type wheels which move by a step-by-step motion from 100 one printing position to the other.

95 It should be understood, however, that while I have here shown and described a specific form of machine embodying my invention, and certain specific applications thereof, these may be modified without exceeding the scope of my invention.

What I claim is:

1. A telegraphic receiver, comprising a type wheel shaft, a type wheel mounted on said shaft to travel longitudinally thereof and rotatable by said shaft on an axis substantially parallel to the line of printing, a second shaft, a print hammer mounted on said second shaft to travel longitudinally 110 thereof and angularly movable thereby, and mechanism to move said type wheel and print hammer longitudinally of their respective shafts, to form the spaces between characters in words as well as between words 115 in a line.

120 2. A telegraphic receiver, comprising a type wheel shaft, a type wheel mounted on said shaft to travel longitudinally thereof and rotatable by said shaft on an axis substantially parallel to the line of printing, a second shaft, a print hammer mounted on said second shaft to travel longitudinally 125 thereof and angularly movable thereby, and mechanism to simultaneously move said type 130

- wheel and print hammer longitudinally of their respective shafts, to form the spaces between characters in words as well as between words in a line.
3. A telegraphic receiver, comprising a type wheel shaft, a type wheel mounted on said shaft to travel longitudinally thereof and rotatable by said shaft on an axis substantially parallel to the line of printing, a second shaft, a print hammer mounted on said second shaft to travel longitudinally thereof and angularly movable thereby, mechanism to move said type wheel and print hammer longitudinally of their respective shafts; and mechanism selectively controlled by the received signals and controlling the operation of said type wheel and print hammer moving mechanism, to form the spaces between characters in words as well as between words in a line.
4. A telegraphic receiver, comprising a type wheel shaft, a type wheel mounted on said shaft to travel longitudinally thereof and rotatable by said shaft on an axis substantially parallel to the line of printing, a second shaft, a print hammer mounted on said second shaft to travel longitudinally thereof and angularly movable thereby, a magnet, and means entirely mechanical and controlled by said magnet to move said type wheel and print hammer longitudinally of their respective shafts, to form the spaces between characters in words as well as between words in a line.
5. A telegraphic receiver, comprising a type wheel shaft, a type wheel mounted on said shaft to travel longitudinally thereof and rotatable by said shaft, a second shaft, a print hammer mounted on said second shaft to travel longitudinally thereof and angularly movable thereby, mechanism to move said type wheel and print hammer longitudinally of their respective shafts, and mechanism controlled by the stopping position of the type wheel shaft to impart rotation to the print hammer shaft.
6. A telegraphic receiver, comprising a type wheel shaft, a type wheel mounted on said shaft to travel longitudinally thereof and rotatable by said shaft, a second shaft, a print hammer mounted on said second shaft to travel longitudinally thereof and angularly movable thereby, and mechanism controlled by the type wheel shaft to move said type wheel and print hammer longitudinally of their respective shafts.
7. A telegraphic receiver, comprising a type wheel shaft, a type wheel mounted on said shaft to travel longitudinally thereof and rotatable by said shaft, a second shaft, a print hammer mounted on said second shaft to travel longitudinally thereof and angularly movable thereby, and mechanism controlled by the stopping position of the type wheel shaft to move said type wheel
- and print hammer longitudinally of their respective shafts.
8. A telegraphic receiver, comprising a type wheel, a printing platen, a screw operatively connected to move said type wheel, a screw operatively connected to move said platen, and mechanism to simultaneously move the two said screws.
9. A telegraphic receiver, comprising a type wheel, a printing platen, a screw to space said type wheel and a screw to space said platen, and mechanical transmission connection between the two said screws.
10. A telegraphic receiver, comprising a double type wheel having two rows of characters whose axis is parallel with the line of printing, a printing platen, means to shift said type wheel and platen longitudinally of the axis of rotation of said type wheel step-by-step for spacing in the line of printing, and means to shift said type wheel to bring one line of characters out of alinement with said platen and the other into alinement therewith.
11. A telegraphic receiver, comprising a series of elements to be selectively operated, a series of disks movable with respect to said elements, means to stop said disks in varying positions to determine the element to be operated, the stopping position of said disks being different from each such element operated, and power driven means to operate the selected element.
12. A telegraphic receiver, comprising a magnet, a type wheel, means to rotate the type-wheel to bring the type thereon into the printing position, printing means cooperative with said type wheel, a sheet to receive the impression, means to move the sheet to form the spaces between lines, means to move the type wheel to form the spaces between letters, means to move the type wheel to the beginning of a new line of printing, and operative connection entirely mechanical between said magnet and said type-wheel rotating means, said lining means, said spacing means, and said type wheel returning means, whereby the one magnet controls all of said means.
13. A telegraphic receiver, comprising a magnet, a sheet to receive the impression, a type-wheel, printing means, means to rotate said type-wheel to the proper printing position, means to produce relative transverse motion between said printing means and said sheet, and means to produce relative longitudinal motion between said printing means and said sheet, and operative connection, entirely mechanical, between said magnet, said type wheel rotating means, and both of said motion producing means.
14. A printing telegraphic receiver, comprising a double type wheel and mechanism to shift said type wheel laterally of its axis of rotation to effect printing from either

- set of characters thereon, printing means coöperative with said type wheel, a plurality of laterally shiftable disks, and mechanism controlled thereby, to control the operation of said printing mechanism from certain of said disks in one shifted position thereof and by other of said disks in another shifted position thereof, and means to shift said type wheel and control disks simultaneously.
15. A telegraphic receiver, comprising a series of controlling elements, to be selectively operated, a series of members movable with respect to said elements and determining the element to be operated, there being one such member for each of said controlling elements, means to stop said members in predetermined positions, and means controlled by the stopping of said members to operate the selected element.
16. A telegraphic receiver, comprising a series of controlling elements to be selectively operated, a series of members movable with respect to said elements, means to stop the movement of said members in predetermined positions to determine the element to be operated, the stopping position of said members being different for each such element operated, and means to move said members by a continuous motion from one of said stopping positions to another.
17. A telegraphic receiver, comprising printing means adapted to be operated after the reception of each signal, a rotatable shaft, and means controlled by the stopping of said shaft in certain selected positions to prevent the operation of said printing means.
18. A telegraphic receiver, comprising printing means, impression receiving material, means to produce relative motion between said printing means and said material, a rotatable shaft, and means controlled by the stopping of said shaft in selected positions to prevent the operation of said motion producing means.
19. In a telegraphic receiver, printing means including a type-wheel, a sheet to receive the impression, means to transmit to said receiver a varied series of electrical impulses, and means to produce relative motion in step-by-step fashion backward or forward between said type-wheel and said sheet according to the impulses received.
20. A telegraphic receiver, comprising printing means including a type-wheel, and electrically controlled means to produce relative step-by-step motion backward or forward between said type-wheel and impression receiving material in said machine.
21. A telegraphic receiver, comprising a double type wheel, a screw, means to rotate said screw to form the spaces between characters, and means to move said screw longitudinally to shift the printing position from one row of type on the type wheel to the other.
22. A telegraphic receiver, comprising a constantly rotating member, a member normally at rest, one or more rollers adapted to lock said normally resting member to said normally moving member, and printing means operated by said normally resting member.
23. A telegraphic receiver, comprising a constantly rotating member, a member normally at rest, one or more rollers adapted to lock said normally resting member to said normally moving member; printing means, and means to produce relative motion between said printing means and impression receiving material, operated by said normally resting member.
24. A telegraphic receiver, comprising a series of selectors, a series of locking members to lock said selectors in operated position, a magnet controlling said selectors, character selecting means controlled by said selectors, and means to print the character corresponding to the selectors operated.
25. A telegraphic receiver, comprising a type wheel shaft, a source of power, signal selecting means, printing means, and type wheel rotating means, a clutch individual to each of said means and adapted to connect it to the source of power, electrically controlled means to operate the signal selecting means, means controlled by the said signal selecting means to operate said type wheel clutch, and means controlled by said type wheel shaft to operate said printing clutch.
26. In a telegraphic receiver, the combination with a rotatable shaft, of a type wheel and a series of selector disks mounted on said shaft for rotation thereby, means to stop said shaft in selected positions according to the signal received to stop said type wheel and disks in corresponding positions, and means controlled by said selector disks when stopped in said selected positions to perform a selected operation.
27. In a telegraphic receiver, the combination with a rotatable shaft, of a type wheel and a series of selector disks mounted on said shaft for rotation thereby, means to stop said shaft in selected positions according to the signal received to stop said type wheel and disks in corresponding positions, and means controlled by said selector disks when stopped in said selected positions to print a selected character.
28. In a telegraphic receiver, a hollow screw, a spring contained in the hollow of said screw and exerting tension on said screw tending to rotate it, means to rotate said screw step-by-step, means operated by the rotation of said screw to produce the spaces between succeeding characters, and

electrically controlled means to release said screw to allow it to return to its starting position under the tension of said spring.

29. A telegraphic printer, comprising a type wheel, a driven shaft carrying said type wheel, a printing platen, means to stop said shaft in positions according to the signal received, and means carried by said shaft adapted to control the operation of said platen according to the stopping position of said shaft.

30. A telegraphic page printer, comprising printing, lining, spacing mechanism, and mechanism for returning to the commencement of a line, a driven shaft, means to stop said shaft in positions according to the signal received, and means adapted to control the operation of all said mechanisms according to the stopping position of said shaft.

31. A telegraphic page printer, comprising printing, lining, spacing mechanism, and mechanism for returning to the commencement of a line, a driven shaft, means to stop said shaft in positions according to the signal received, and means carried by said shaft adapted to control the operation of all said mechanisms according to the stopping position of said shaft.

32. A page printing telegraphic receiver, comprising printing, spacing, and lining mechanisms, a magnet, and means entirely mechanical forming an operative connection between said mechanisms and said magnet whereby said mechanisms are all under the initial selective control of the one magnet.

33. A page printing telegraphic receiver, comprising printing, spacing, and lining mechanisms, a magnet, means entirely mechanical forming an operative connection between said mechanisms and said magnet whereby said mechanisms are all under the initial control of the one magnet, and a mechanical timing device started into operation by said magnet on the reception of each signal, and controlling the timing of said mechanisms.

34. A page printing telegraphic receiver, comprising printing, spacing, and lining mechanisms, a magnet, mechanical selecting means for controlling the operation of said mechanisms, and operative connection entirely mechanical between said magnet and said selecting means.

35. A page printing telegraphic receiver, comprising printing, spacing, and lining mechanisms, a mechanical combination mechanism common to all said mechanisms for controlling their operation, mechanical selecting mechanism controlling the operation of said combination mechanism, a mechanical timing device comprising a body having a natural period of motion, a magnet, and operative connection entirely me-

chanical between said magnet, timing device 65 and selecting mechanism.

36. A telegraphic receiver, comprising a rotatable type wheel, means to rotate said type wheel by a continuous motion from one printing position to another and to stop said type wheel in the printing positions, and means to move said type wheel transversely of its plane of rotation to effect the spacing from one character to another on the record receiving material. 75

37. A telegraphic receiver, comprising a rotatable type wheel, means to rotate said type wheel by a continuous motion from one printing position to another and to stop said type wheel in the printing positions, means 80 to move said type wheel transversely of its plane of rotation to effect the spacing from one character to another on the record receiving material, a printing platen and means to move said platen transversely of 85 the plane of rotation of said type wheel.

38. A recording telegraphic receiver, comprising a rotatable shaft, means to stop the rotation of said shaft in various angular positions corresponding respectively to the signals received, a recording element, a spring for imparting motion to said element to record the signals, means normally holding said element against the tension of said spring, a control shaft and a cam carried 95 thereby permitting the release of said holding means, and a detent controlled by said first mentioned shaft to prevent the operation of said release in certain predetermined stopping positions of said first mentioned 100 shaft, and allowing its operation in other stopping positions of said shaft.

39. A printing telegraphic receiver, comprising, a rotatable shaft, a type-wheel mounted thereon to rotate with said shaft, 105 means to stop the rotation of said shaft in various angular positions corresponding respectively to the signals received, a printing platen for said type wheel, a spring for imparting motion to said platen for recording the signals, means normally holding said platen away from said type-wheel against the tension of said spring, a control shaft and a cam carried thereby permitting the release of said holding means, and means controlled by said type wheel shaft to prevent the operation of said release in certain predetermined stopping positions of the type wheel shaft. 115

40. A printing telegraphic receiver, comprising a rotatable shaft, a type-wheel mounted thereon to rotate with said shaft, means to stop the rotation of said shaft in various angular positions corresponding respectively to the signals received, a printing platen for said type-wheel, a spring for imparting motion to said platen in the direction of said type-wheel to record the sig- 120 125

- nals, means normally holding said platen away from said type-wheel against the tension of said spring, a control shaft and a cam carried thereby permitting the release 5 of said holding means, and a detent controlled by said type wheel shaft to prevent the operation of said release in certain predetermined stopping positions of the type-wheel shaft.
- 10 41. A recording telegraphic receiver, comprising a rotatable shaft, signal recording means mounted on said shaft, means to stop the rotation of said shaft in various angular positions corresponding respectively to the 15 signals received, a movable recording element adapted to coöperate with said recording means, a spring for imparting motion to said element in the direction of said recording means, means normally holding said 20 element away from said recording means against the tension of said spring, a control shaft and a cam carried thereby permitting the release of said holding means, and a detent controlled by said first mentioned shaft 25 to prevent the operation of said release in certain predetermined stopping positions of the first mentioned shaft, and means operated by a portion of said holding means to move said recording means and element 30 longitudinally of said first mentioned shaft.
42. A printing telegraphic receiver, comprising a rotatable type-wheel shaft, a type-wheel mounted thereon to rotate with said shaft and move longitudinally thereof, means to stop the rotation of said shaft in various angular positions corresponding respectively to the signals received, a printing platen for said type-wheel, a spring for imparting motion to said platen in the direction of said type-wheel, means normally holding said platen away from said type-wheel against the tension of said spring, a control shaft and a cam carried thereby permitting the release of said holding means, 45 and a detent controlled by said type wheel shaft to prevent the operation of said release in certain predetermined stopping positions of the type wheel shaft, and means operated by a portion of said holding means to move said type-wheel and platen longitudinally of said type-wheel shaft.
43. A printing telegraphic receiver, comprising a rotatable type-wheel shaft, a type-wheel mounted thereon to rotate with said shaft and move longitudinally thereof, means to stop the rotation of said shaft in various angular positions corresponding respectively to the signals received, a printing platen for said type-wheel, a spring for imparting motion to said platen in the direction of said type-wheel, means including a slide for normally holding said platen away from said type-wheel against the tension of said spring, a control shaft and a cam carried thereby permitting the release of said 60
- slide, and a detent controlled by said type wheel shaft to prevent the operation of said slide in certain predetermined stopping positions of the type wheel shaft, and means including a ratchet tooth on said slide to move said type-wheel and platen longitudinally of said type-wheel shaft.
44. A telegraphic recorder comprising a paper feed roll, a ratchet and pawl for operating said roll, a shaft and means to rotate said shaft the same amount for each character to be recorded, a cam operated by said shaft, a spring acting to force said ratchet against said cam, a second shaft and means to rotate the same a different amount for each character to be recorded, and means operated by said last named shaft to permit said pawl to travel in the direction of said cam in a certain stopping position of said last mentioned shaft, but preventing said movement in other stopping positions of said last mentioned shaft.
45. A telegraphic recorder comprising a paper feed roller, a ratchet for operating said roller, a slide having a pawl tooth adapted to operate said ratchet, a shaft and means to rotate said shaft the same amount for each character to be recorded, a cam operated by said shaft, a spring acting to force said slide against said cam, a second shaft and means to rotate the same a different amount for each character to be recorded, and a slotted disk operated by said last named shaft, a lever pivoted to said slide and having a nose adapted to engage with the slot in said disk in a predetermined stopping position of said last named shaft to permit said slide to travel in the direction of said cam, the said slotted disk co-operating with said lever to prevent said movement in other stopping positions of said last mentioned shaft.
46. A page recording telegraphic receiver comprising, a type-wheel shaft, a type-wheel mounted thereon for rotation and for movement longitudinally of said shaft, a rotary member having a spiral shoulder thereon, operative connection between said shoulder and type-wheel for moving said type-wheel longitudinally of said shaft, a spring tensioned by the rotation of said rotary member in one direction, a ratchet, and pawl mechanism for rotating said member to impart forward movement to said type-wheel longitudinally of said shaft and to tension said spring, and means to release said ratchet to permit said shaft to rotate said shouldered member backward for moving said type-wheel backward longitudinally of its shaft, said mechanism comprising a cam provided with a drop, a power shaft for operating said cam, a slide adapted to engage said cam, a spring forcing said slide against said cam, a control lever connected to said slide, and a disk carried by said type- 130

wheel shaft coöperating with said lever to permit the movement of said slide in the direction of said cam only in a predetermined stopping position of said type-wheel shaft, and an extension on said slide adapted to operate the ratchet of said pawl to release said shouldered member to permit it to rotate backward under the action of its spring.

5 47. A telegraphic receiver comprising signal recording elements movable step-by-step to form the spaces between the recorded characters, and mechanism operable according to the signals received to back space said elements.

10 48. A telegraphic receiver comprising signal recording elements movable step-by-step to form the spaces between the recorded characters, and mechanism operable according to the signals received to back space said elements, and a mechanical combination device controlling the operation of said back spacing mechanism.

15 49. A telegraphic receiver comprising signal recording elements movable step-by-step to form the spaces between the recorded characters, a shaft adapted to stop in predetermined positions depending upon the signals received, and means controlled by the stopping of said shaft in certain of said positions to back space said elements.

20 50. A telegraphic receiver comprising signal recording elements including a type-wheel movable step-by-step longitudinally of its axis of rotation to form the spaces between the recorded characters, and mechanism operable according to the signals received to back space said type-wheel.

25 51. A telegraphic receiver comprising signal recording elements including a rotary type-wheel movable step-by-step longitudinally of its axis of rotation to form the spaces between the recorded characters, and mechanism operable according to the signals received to back space said type-wheel, and a mechanical combination device controlling the operation of said back spacing mechanism.

30 52. A telegraphic receiver comprising signal recording elements including a rotary type-wheel movable step-by-step longitudinally of its axis of rotation to form the spaces between the recorded characters, a shaft carrying said type-wheel and adapted to stop in predetermined positions depending upon the signals received, and means controlled by the stopping of said shaft in certain of said positions to back space said elements.

35 53. A telegraphic receiver comprising, a double type-wheel having two substantially parallel rows of type located in different vertical planes, a platen for said type-wheel, means to move said platen and type-wheel simultaneously in a direction longitudinally of the axis of rotation of said type-wheel,

and means to shift said type-wheel in said direction without shifting said platen.

54. A telegraph receiver, comprising a magnet, an armature operated thereby, a spring operated balance for timing the operation of the receiving mechanism, a stop member normally holding said balance against movement, an arm pivoted to said stop member and adapted to lie in the path of said armature for engagement thereby to release said stop from said balance, mechanism operating before the completion of a recorded signal to remove said arm from the path of said armature, and mechanism to cause said member to stop the movement of said balance at the end of a signal and return said arm to the path of said armature.

55. A telegraphic receiver, comprising recording means adapted to be operated after the reception of each signal, a rotatable shaft, and means controlled by the stopping of said shaft in certain selected positions to prevent the operation of said recording means.

56. A telegraphic receiver, comprising recording means, impression receiving material, means to produce relative motion between said recording means and said material, a rotatable shaft, and means controlled by the stopping of said shaft in selected positions to prevent the operation of said motion producing means.

57. A telegraphic page recorder, comprising recording, lining, spacing mechanism, and mechanism for returning to the commencement of a line, a driven shaft, means to stop said shaft in positions according to the signal received, and means adapted to control the operation of all said mechanisms according to the stopping position of said shaft.

58. A telegraphic page recorder, comprising recording, lining, spacing mechanism, and mechanism for returning to the commencement of a line, a driven shaft, means to stop said shaft in positions according to the signal received, and means carried by said shaft adapted to control the operation of all said mechanisms according to the stopping position of said shaft.

59. A page recording telegraphic receiver, comprising, recording, spacing, and lining mechanisms, a magnet, and means entirely mechanical forming an operative connection between said mechanisms and said magnet whereby said mechanisms are all under the initial selective control of the one magnet.

60. A page recording telegraphic receiver, comprising recording, spacing, and lining mechanisms, a magnet, means entirely mechanical forming an operative connection between said mechanisms and said magnet whereby said mechanisms are all under the initial control of the one magnet, and a mechanical timing device started into operation

by said magnet on the reception of each signal, and controlling the timing of said mechanisms.

61. A page recording telegraphic receiver, comprising recording, spacing, and lining mechanisms, a magnet, mechanical selecting means for controlling the operation of said mechanisms, and operative connection entirely mechanical between said magnet and said selecting means.

62. A page recording telegraphic receiver, comprising recording, spacing, and lining mechanisms, a mechanical combination mechanism common to all said mechanisms for controlling their operation, mechanical selecting mechanism controlling the operation of said combination mechanism, a mechanical timing device comprising a body having a natural period of motion, a magnet, and operative connection entirely mechanical between said magnet, timing device and selecting mechanism.

63. The combination with a transmission line, of a source of voltage on said line, a series of transmitting contacts normally open in said line, a recording mechanism individual to each of said contacts, a switch in parallel with each of said normally open contacts, and means forming a part of each of said recording mechanisms to render said mechanisms individually non-operative when all of said switches are closed.

64. The combination with a transmission line of a source of voltage on said line, a series of transmitting contacts normally open in said line, a plurality of printing telegraphic receivers in series in said line, a switch in parallel with each of said normally open contacts, and mechanism forming a part of each of said receivers and adapted to automatically render them individually non-operative when all of said switches are closed.

65. The combination with a transmission line, of a source of voltage on said line, a series of transmitting contacts normally open in said line, means individual to each of said contacts for selectively operating the same, a plurality of printing telegraphic receivers in series in said line, a switch in parallel with each of said normally open contacts, and mechanism forming a part of each of said receivers and adapted to automatically render them individually non-operative when all of said switches are closed.

66. The combination with a transmission

line, of a source of voltage on said line, a series of transmitting contacts normally open in said line, means individual to each of said contacts to selectively operate the same to transmit to line a series of electrical impulses, a plurality of recording telegraphic receivers in said line, a switch in parallel with each of said normally open contacts, and means to automatically render said recording mechanisms inoperative when all of said switches are closed and operative by any individual contact when its corresponding switch only is open.

67. A receiver for electric telegraphs in which the signals are formed by combinations of electrical impulses, comprising a movable control member, two devices normally preventing said member from operating, one of said devices invariably tending to permit the operation of said member upon the receipt of each signal, and the other of said devices tending to permit the operation of said member on the receipt of certain signals only and controlled by and acting only after the reception of the complete combination of code impulses which form the respective signals, the two said devices co-operating to simultaneously permit of the operation of said control member.

68. A receiver for electric telegraphs in which the signals are formed by combinations of electrical impulses, comprising a rotatable shaft, means acting subsequently to the reception of the complete combination of code impulses forming the respective signals and controlled thereby to stop said shaft in various angular positions corresponding respectively to such signals, a second rotatable shaft and means to rotate the same invariably for each signal received, a notched control disk operated by said first mentioned shaft, a detent controlled according to the stopping positions of said first mentioned shaft and control disk, a cam operated by the second mentioned shaft, and a control member operatively associated with said detent and cam, said cam tending to permit of its operation invariably on the receipt of each signal and the detent and control disk preventing its operation except on the receipt of certain signals.

In testimony whereof I affix my signature in presence of two witnesses.

LOUIS MAXWELL POTTS.
